FEED HEAD FOR TABULATORS

John Royden Peirce, New York, N. Y., assignor,
by mesne assignments, to International Busi-
ness Machines Corporation, New York, N. Y., a
corporation of New York

Application September 13, 1930
Serial No. 481,662

22 Claims. (Cl. 101—93)

This invention relates to record controlled ac-
counting machines and more particularly to
translating mechanism in combination with a
combined numerical and alphabetical printer
5 which selects certain printing characters for
operation by the multiple index system and others
by the single index point system.

An object of the invention is to provide a trans-
lating mechanism for an alphabetical printer
10 requiring cyclic operations for all possible print-
ing operations, that analyzes cards during a con-
tinuous uninterrupted feeding operation.

Accounting machines of this nature are
generally controlled by record cards divided into
15 columns in which perforations or index points
may be placed to indicate different characters.
The controlling cards are of two general types,
in one of which only one perforation is placed
in a card column and in the other of which a
20 combination of index point perforations may be
placed in each column. Obviously the number
of different characters which can be represented
on cards of the first type is limited to the actual
number of index point positions in a card column
25 while on the second type of cards the number of
possible characters is far in excess of the actual
number of index point positions. The machines
operating from the single hole cards are some-
what simpler in construction than those oper-
30 ating from the combination hole cards and are
particularly adapted to electrical operation. It is
often desirable to combine the advantages result-
ing from the saving in card space due to com-
binational hole systems with the advantages re-
35 sulting from the simpler operation and construc-
tion or electrical operation of the machines oper-
ating in accordance with the system of single
hole cards.

The single hole card machines are generally
40 provided with analyzing brushes, one for each
card column, beneath which the cards are passed
with a continuous motion. Manifesting devices,
which may be either accumulating or printing
mechanisms, are driven by means operated syn-
45 chronously with the feed of each card beneath
the brushes and when a brush encounters a per-
foration a circuit is closed momentarily, the re-
sulting current pulse either connecting the mani-
festing devices to or disconnecting them from
50 their driving means. The movement of the mani-
festing means during the card feeding cycle is
then either directly or inversely proportional to
the differential location of the index point on the
card and may, therefore, indicate or register the
55 character represented by the index point.

As is well known the Hollerith card is provided
with a plurality of vertical rows or columns of
index points usually numbered 0 to 9, but having
60 two extra positions known as the 11th and 12th
positions. The first ten are digit values; and a

hole punched at one of these points will, when
the card is run through the proper machine, cause
a reproduction of that digit value in some form
usually by printing the digit or by exhibiting the
same in counter wheels along with other received
65 digit values.

The present invention uses the standard Hollerith
70 card provided with columns of ten or twelve
index points to represent not only the digits,
but also the entire alphabet and other arbitrary
characters. According to the present system, in-
stead of perforating one hole for selection of
75 certain characters, two holes are punched in a
column, which taken together form a combina-
tional hole designation. The first hole, accord-
ing to its position, serves to designate which of
several groups of characters contains the char-
acter to be selected, and the second hole design-
ates which of the several characters in the des-
ignated group is to be selected. When a single
80 index point is used to select certain other char-
acters that index point is used both to select a
group of characters as well as one in that par-
ticular group. Mechanism is then brought into
85 operation to print such characters.

The invention is particularly concerned with
90 avoiding complicated circuits with their selective
switches or mechanical cam and latch systems,
one or the other of which have previously been
essential to the proper functioning of translat-
ing mechanism of this type.

95 Preferably this is accomplished by the use of
a pair of contact controlling sliders, one pair for
each card column and arranged to be positioned
by a single magnet. The sliders move synchro-
nously with the passage of the 11 and 12 holes
100 past the upper analyzing brushes and according
to their setting prepare circuits which when the
card passes the lower brushes will control the
normal circuits through the holes in index posi-
tions 9 to 0 so that the type bars may present
105 the corresponding characters to the printing line.

The alphabetical type bars are arranged to
move synchronously with the passage of the cards
110 past the lower brushes and are provided with
stops thereon so arranged that during the pas-
sage of a single index point past the lower brushes,
three stops will traverse the type bar stopping
pawl in succession. The lower brushes are of
115 greater width in a columnar direction than those
usually provided in machines of this type, being
so constructed that contact will be made through
a hole in any index position during the interval
that the three characters corresponding to such
perforation are successively presented to the
printing position.

120 A single distributor device is provided whose
function is to complete three distinct circuits
through the perforations in the card for each in-
dex position, the timing of these circuits corre-

sponding to the presentation of the three characters allotted to the particular index points.

The principal object of the invention therefore is to provide novel translating mechanism for 5 accounting machines to the end that the construction and operation of parts and the cooperation between parts may be simplified.

Another object is to provide circuit controlling devices for accounting machines so that a perforation in a single index position may control 10 the printing of a plurality of characters depending upon the location of the control hole accompanying such perforation.

Further and other objects of the present invention will be hereinafter set forth in the accompanying specification and claims and shown 15 in the drawings which by way of illustration show what I now consider to be a preferred embodiment of the invention.

20 In the drawings:

Fig. 1 is an outside view of the translating mechanism located adjacent to the card feeding and analyzing devices;

25 Fig. 2 is a sectional view of the translating mechanism and card analyzing devices looking in the same direction as Fig. 1;

Fig. 3 is an enlarged position view of the lower portion of the translating device looking in the opposite direction from Fig. 2;

30 Fig. 4 is a diagrammatic showing of the relative arrangement of the card analyzing brush and the type bar positioning pawl;

Fig. 5 is a partial plan section of the translating mechanism and operating cams therefor.

35 The section is taken on line 5-5 of Fig. 2;

Fig. 5a is a sectional detail of contact controlling devices;

Fig. 6 is a view of an alphabetical type bar and controlling mechanism therefor;

40 Fig. 7 is an isometric view of the circuit controlling distributor;

Fig. 8 is a view of a card showing the coding arrangement of the digits and alphabetical characters;

45 Fig. 9 is a wiring diagram of the electric circuit of the device.

Card feeding mechanism

Power for driving the various mechanisms is 50 derived from a driving shaft 20 carrying a gear 21 meshing with a ring gear 22 (Fig. 1). The record cards are fed singly from a supply hopper 23 by the usual card picker mechanism which in the present embodiment comprises a slidably 55 mounted reciprocable plate 24 (Fig. 2) carrying a picker knife 25 for cooperation with the record cards. The plate 24 has a pin and slot connection 26 to an arm 27 secured to a shaft 28 which carries at its end an arm 29 connected by a link 60 30 (Fig. 1) to a gear 31, it being observed that the link is eccentrically mounted on the gear 31 and that the latter is in mesh with ring gear 22. Each reciprocation of the arm 27 will cause a 65 card to be fed from the hopper to the analyzing mechanisms.

The record cards are diverted from their initial rectilinear movement by a track which is substantially concentric with respect to the center of gear 22 and the cards in passing are presented 70 to two sets of analyzing brushes 32 and 33 which sense the perforations of the record cards. The feeding of the record cards is effected by concentrically arranged pairs of feeding rollers 34 which frictionally grip the cards and cause them 75 to be fed in a direction determined by the shape

of the track plates. The extremities of the shafts of rollers 34 are provided with gears 35 which have driving engagement with ring gear 22 and drive their motion therefrom.

The cards pass from the last pair of rollers 34 80 to any suitable stacker mechanism such as that designated by reference character 36 and which is of the rotary type, the drum shaft 37 having attached thereto a gear 38 meshing with a gear 39 secured to gear 31. The cards are thus fed to a stack 40 one behind the other in precisely the same order they were in originally.

85 As the cards pass through the feeding section current is supplied to the upper brushes 32 during the period that the 11 and 12 index point positions of the card are in cooperation with the brushes. These two index point positions are adapted to control the setting of the translating mechanism to be described later. As the cards 90 continue through the feeding mechanism they cooperate with the lower brushes 33 to which current is supplied during the interval that all the index point positions are in cooperation with the brushes. The lower brushes 33 are constructed of greater width in a columnar direction of 95 the card to obtain longer duration of contact through the perforations for a purpose to be explained later.

99 Referring now to the card (Fig. 8) a conventional Hollerith card is illustrated and the usual 105 digit perforations are indicated in the conventional manner. These single hole perforations are located at the various index positions in accordance with their value. The alphabetical characters B to L inclusive are represented by 110 two perforations, one in the 11 index point position and the other in one of the index positions 0 to 9. The alphabetical characters N to Y inclusive have a perforation in the 12 index position and one in positions 0 to 9. The letter A 115 has a single perforation in the 11 position and the letter M in the 12 position. The upper brushes 32 are adapted to sense the 11 and 12 positions and set up the circuit controlling devices in the translating mechanism. The lower 120 brushes 33 in sensing the card beginning with the 9 position will sense the perforations and in cooperation with a distributing mechanism in the translating device select the proper character for printing. If the upper brushes find a perforation in the 11 position, the translating mechanism will be positioned to select one of the characters included in the zone having such supplementary perforation. If the upper brushes sense a perforation in the 12 position, one of the remaining alphabetical characters is to be printed, while if the upper brushes find no perforations in either of these index positions, the character to be printed will be a digit.

125 Translating mechanism

130 Referring now to Fig. 1, the cam shaft 45 of the translating mechanism is adapted to be driven in the direction indicated by the arrow by ring gear 22 through the gearing generally 135 designated 46. The gear ratio is such that shaft 45 makes one-half revolution for each revolution of shaft 20 which as has been explained is a cyclic shaft turning once for each card fed through the feeding device.

140 Driven from shaft 45 through gears 47 is a shaft 48 carrying at its opposite end a distributing commutator 49 having brushes 50 cooperating therewith. The commutator is provided 145 with a common conducting ring 51 and a con-

centrically arranged series of conducting inserts 52 electrically connected to the ring 51. A second set of inserts 53 arranged in a similar manner are also connected to the ring 51 as is also 5 a third ring of segments designated 54. Distributor 49 makes one revolution per card cycle and the device is so timed that as the card is passing below the lower brushes 33 the inserts 52 are successively contacting the brushes 50 in time with the cooperating of the index point positions with the lower brushes and during the passage of any one index position by the brushes 33 the three adjacent inserts 52, 53, 54 corresponding to such index position will successively 10 cooperate with their brushes 50.

The lower brushes 33 are constructed of sufficient width so they maintain contact through a perforation in the card during the cooperation of the three successive inserts 52, 53, 54 with their 20 corresponding brushes 52a, 53a, 54a.

In a manner to be explained in connection with the circuit diagram the flow of current through the lower brushes will be controlled in accordance with the reading obtained by the upper brushes 25 to pass through one of the brushes 52a, 53a or 54a.

In Figs. 2 and 3 a magnet 55 is provided for each card column. Each magnet has an armature 56 pivoted at 57 and provided with a spring 58 which is adapted to hold the armature away from the magnet. A vertical link 59 urged upwardly by spring 60 at its upper end is connected to a pivoted stopping pawl 61 at its lower extremity and is normally adapted to be latched in its 35 lower position by armature 56 as shown in Fig. 2.

A slider 62 is mounted for horizontal movement and is provided with notches 63 adapted to cooperate with the nose of pawl 61. The operation of the parts is such that as the sliders 62 move toward the left, as viewed in Fig. 3, under the influence of their springs 64, the notches 63 approach the nose of pawl 61 as the 11 and 12 index point positions of the card pass under the brushes 32. A perforation in the 11 position will cause energization of magnet 55 and the pawl 61 will be permitted to drop into engagement with the first notch 63 thus interrupting the further movement of the slider 62. A perforation in the 12 position will cause the pawl 61 to engage the second notch. The absence of a perforation in either of these two index point positions will permit the slider 62 to assume a third position.

Two sliders 62 are provided for each card column and they are adapted to move to the left in alternate cycles so as to permit the continuous feeding of cards. Both of the sliders are positioned by the same pawl 61 and while one slider is being positioned, the other is restoring and vice versa. One set of sliders is provided with depending projections 65 and the other has projections 66 cooperating with restoring bars 67 and 68 respectively.

Bar 68 is secured at its extremities in the horizontal link 69 pivoted at one end to an arm 70 loose on shaft 71 and pivoted at its other end to an arm 72 secured on shaft 73. Shaft 73, as viewed in Figs. 1 and 5, carries at its outer end a cam follower arm 74 cooperating with a cam 75 on the shaft 45. In a similar manner the restoring bar 67 is connected to shaft 71 which in turn has a follower arm 76 secured thereto, cooperating with the cam 77 on shaft 45. Springs 78 are provided in Fig. 3 to move the bars 67, 68 to the left to permit the sliders 62 to operate.

A restoring bail 70 is secured to shaft 80 (Figs. 3 and 5) which in Fig. 1 carries a spring pressed follower arm 81 in cooperation with a cam 82. The timing of the operation of the bail 79 is such that the pawls 61 are restored to their latched position shortly after they have been tripped and since shaft 45 upon which the cam 82 is mounted rotates but once for each two card cycles, the cam 82 is provided with two oppositely located camming surfaces which operate the shaft 80 twice during the revolution of the shaft.

Each slider 62 has pivoted thereto, as shown in Fig. 3, an interposer 83 having a depending projection 84 adapted to cooperate with plungers 85 disposed in the path of movement of the projections 84. A single set of three plungers 85 is provided for each interposer 83.

Each interposer has pin and slot connection with a bell crank 86 loosely pivoted at 87. The bell crank 86 cooperating with one of each pair of interposers 83 has its free end engaged by a bail 88 while the remaining bell cranks have their free ends engaged by a bail 89. Rocking of either bail in a clockwise direction, as viewed in Fig. 3, will through the associated bell cranks, move the interposers 83 in a downward direction and depress one of the plungers 85 as shown. In the position shown in Fig. 3 the magnet 55 has been energized by the upper brushes under control of an 11 hole thus intercepting the slider 95 62 at the first notch 63. This in turn has located the projection 84 above the longest plunger 85. Immediately following such positioning of interposer 83 the bail 88 has been rocked in a clockwise direction lowering interposer 83 and depressing plungers 85 to close contact 90. As seen in Fig. 5a both sets of plungers 85 associated with a single card column or pair of sliders 62 are adapted to close a single set of contacts. Thus, depression of either of a pair of plungers 85 in 100 the 11 position will close contact 90.

Bail 88 will remain in its clockwise position holding the contact 90 closed during the passage of the card by the lower brushes and since pawl 61 has been restored immediately following the lowering of interposer 83 the other slider 62 of the pair corresponding to the card column in question may now move to the left to position in accordance with the perforations in the next succeeding card and will be in position with its interposer in readiness to be depressed immediately after the previous card has been completely read by the lower brushes 33. At such time bail 88 will be rocked in a counterclockwise direction 105 raising the interposers 83 which have been depressed so that they may restore with their connected sliders.

At the same time bail 89 is rocked in a clockwise direction lowering the newly positioned interposers 83 and impressing a new setting upon its set of plungers 85. If the interposer were positioned under control of a 12 perforation, projection 84 would have advanced to the center plunger causing it to be depressed to close contact 91. Where no perforation is encountered by the upper brush 32, the interposer 84 will advance to its extreme position where projection 84 lies over the shortest plunger 85 causing it to close contact 92.

In this manner a single set of contacts 90, 91, 92 are utilized to be positioned for each successive card and to control the readings of this card obtained by the lower brushes 33. In their downward movement the interposers 83 engage a resilient cross bar 93 which seats into suitable notches 110 115 120 125 130 135 140 145 150

in the lower edges of the interposers. The sides of the notches are so inclined that as the interposers move downwardly into engagement with the bar 93 the interposers and their connected 5 sliders 62 will be forced slightly to the right, as viewed in Fig. 3. This will cause the notches 63 which are in engagement with the pawl 61 to move slightly away from the noses of the pawls 61.

This is to permit the free operation of the 10 pawls 61 during the next succeeding cycle without interference by the notches of the sliders 62 which will not have been restored at the time the alternate slider is being positioned.

The bail 88 has a pair of links 94 connected at 15 its extremities which connect to arms 95 secured on a shaft 96 (see Fig. 5). An arm 97 secured upon the extremity of shaft 96 is connected by a link 98 to an arm of a member 99 which has a follower roller in engagement with a cam 100 secured upon the shaft 45. The bail 89 has a pair of links 101 at its extremities connected to arms 102 secured upon shaft 103 which shaft carries an arm 104 having connection through a link 105 to a follower member 106 which has a roller 20 in cooperation with the cam 100. The contour of cam 100 is such that the bails 88, 89 reverse their positions each half revolution of the shaft 45 as may be seen in Fig. 3.

Pivoted to bail 79 at 107 is an upwardly extending link 108 (see also Fig. 1) suitably guided and provided with pins 109 cooperating with spring 30 pressed arms 110 secured upon rods 111. In Fig. 3 the rods 111 carry restoring plates 112 adapted to engage the upper arms of armatures 56 to restore the same when the bail 79 is operated.

Printing mechanism

Referring to Fig. 6 the cyclic shaft 20 carries a 40 pair of complementary cams 115 which cooperate with the rollers of the cam follower bell crank 116 secured upon a rod 117 to which is also attached an arm 118 having link connection to an arm 119 secured to a pivot rod 120. A pair of arms 121 is secured at opposite ends of rod 120 and carries a bar 122 and depending links 123. The links 123 are connected at their lower ends to a bail 124 pivoted at 125. A plurality of type bars 126 are mounted for vertical reciprocation and are connected at their lower ends by links 127 50 to individual levers 128 pivoted at 125. The upper edges of levers 128 are urged by springs 129 against bail 124.

The operation is such that as the bail 124 is 55 rocked in a clockwise direction spring 129 will draw upwardly on lever 128 to elevate the type bar and during the return movement of bail 124 the levers 128 will be moved downwardly to restore the type bars. Each type bar is provided with a series of notches 130 adapted to cooperate with a stopping pawl 131 held in normal position out of engagement with the notches by a latch 132. Energization of magnet 133 will rock the latch 132 to release the pawl 131 so it may intercept the upward movement of the type bar. After the type bars have been positioned in a selected column in printing position opposite the platen 134 the usual printing hammer 135 is tripped to cause an impression to be made on the record in the usual manner. The type bars move upwardly to present the various type 60 to printing position in synchronism with the passage of the record card by the lower brushes 33.

Referring now to Fig. 4 in which is shown 75 diagrammatically the relative positions of the parts

now being considered, during the passage of a single index point position by the brush 33 the three notches 130 corresponding to the three characters which have a perforation in that particular index position will move past the stopping pawl 131 and the corresponding type will move past the printing position of the platen. For instance, an inspection of the card in Fig. 8 will disclose that the digit 5 and the alphabetical characters G and T all have a perforation in the 5 index point position. In Figs. 4 and 6 these three characters are located adjacent to one another so that as the 5 index point position traverses the brush 33 the notches 130 representing 80 5, G and T will successively pass the toe of the pawl 131. Brush 33 is of sufficient width to maintain contact through the perforations during the passage of the three related notches and the distributing commutator under control of the upper brushes will determine at which point in the passage of a trio of notches the pawl 131 is to be tripped.

For instance, reconsidering a perforation in the 5 index point position, the presence of an accompanying perforation in the 12 position to 100 represent the letter T will set the distributing mechanism so that the tripping of the pawl 131 as the 5 index point position is cooperating with brush 33 will be delayed until the notches corresponding to 5 and G have passed. Likewise, 105 if an 11 perforation accompanies the 5 hole, pawl 131 will be tripped immediately after the 5 has passed. And thirdly, if there is no controlling perforation in the 11 or 12 position the pawl 131 will trip earlier to catch the type bar in 5 position. 110

Referring now to the wiring diagram of the device (Fig. 9) the upper brushes are represented at 32 and the lower brushes at 33. The circuits will flow through the device from one side of line 140 to the opposite side 141. A cam contact 115 142 is provided to permit current to flow from line 140 to the brushes during the passage of the index points 11 and 12 only. The occurrence of a perforation in either of these positions will complete a circuit from line 140, contact 142, 120 common bar 143, perforation in the card, brush 32, wire 144, magnet 55, wire 145, to other side of line 141. This as has already been explained in detail in connection with Fig. 3 will position the corresponding slider 62 so that either of the 125 contacts 90 or 91 will close. If no perforation is sensed by the brush in these two index positions, the contact 92 will be closed. In the wiring diagram the uppermost set of contacts 90, 91 and 92 has been positioned to indicate that the 130 character has no controlling perforation 11 or 12. Consequently, contact 92 is closed. In the second set, contact 91 is closed, indicating a 12 perforation. In the third set, contact 90 is closed to represent a character in the field having a 135 perforation in the 11 position. These contacts, as has been explained, are so positioned during the passage of the card by the upper brushes 32 and remain in this position during the passage of the same card by the lower brushes 33. Current is supplied to the brushes 33 from line 141, through a cam contact 146 and common bar 147.

The distributing commutator 49, shown in development, has its three brushes 52a, 53a, 54a, connected to wires 52b, 53b, 54b, to which are 145 respectively connected the contacts 92, 90, 91, having in mind that during the passage of any index point by the lower brushes the three commutator inserts 52, 53, 54 will successively 150 cooperate with their respective brushes while the 150

brush 33 is making contact through the perforation in the card in that position.

The manner of selection may more readily be explained by means of a specific example: Assume for instance that the column containing a 9 perforation passed through the machine if there were no control perforation contact 92 would have been closed as the card passed the upper brushes. Arriving at the lower brushes the circuit through the 9 hole would be completed immediately upon the presentation of insert 54 to its corresponding brush 54a. The completed circuit about to be traced will then intercept the type bar to present a nine to printing position. The circuit flows from line 140, to common ring 51 of the distributor insert 54 of the 9 position, brush 54a, wire 54b, contact 92, magnet 133, wire 148, corresponding brush 33, bar 147, contact 146, back to line 141. If the character perforated in the column represents the letter Y, the circuit would have been completed when the insert 53 of the 9 position came to contact with its brush 53a and the circuit would follow to the wire 53b to the lowest contact 91 and thence through magnet 133 in the same manner to interrupt the type bar in the last of the trio of notches corresponding to the 9 index point position of the card.

According to the card (Fig. 8) it will be observed that two characters A and M are represented by control holes in the 11 and 12 positions only. Considering a perforation in the 11 position only the sensing of the column by the upper brushes 32 will cause closure of contact 90 in the regular manner. During the rotation of the distributor 49 a special insert 53c will contact with the brush 53a immediately after the passage of the last three characters associated with the zero perforation.

The sensing of the M perforation in the 12 position will cause closure of contact 91 and the consequent later completion of the circuit when a special insert 53c contacts with brush 52a. These two inserts 52c and 53c are so located that the time of completion of the circuit will follow immediately after the sensing of the zero index position by the lower brushes. This is done to maintain a uniform spacing between the various type elements, as will be noted in Figs. 4 and 6. The configuration of the type bar cams 115 is such that as the card is passing the sensing brushes between the 11 and 12 index point positions, the type bar is rising at a lesser rate and the "M" position reaches the printing line simultaneously with the sensing of the 12 index point positions.

After a card has completely passed the lower brushes, the contacts 90, 91, 92 are restored and immediately set to a new combination of positions in accordance with the reading of the next succeeding card about to pass the lower brushes. This reading, as will be recalled, was taken on the passage of this card by the upper brushes 32 and its imposition upon the contacts 90, 91, 92 delayed until the card approached the lower brushes. In this manner the same set of contacts 90, 91, 92 may be utilized for each successive card without the necessity of skipping any card reading cycles or the provision of an alternate set of contacts which is usually necessary in other translating devices of this character where the complete sensing of a card requires two cycles, one for determining the zone and the other for selecting the particular position in that zone.

While there has been shown and described and pointed out the fundamental novel features of the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims:

1. In a card controlled machine, means for sensing a card in motion, a type bar, a plurality of groups of printing characters carried by said bar, selector means controllable by a perforation in a card, adapted to select a character in each group for operation, means controllable by a perforation in a card for selecting one of said groups to present the selected character therein to printing position while the card is in motion and means for causing said characters to print upon a record. 95

2. In a card controlled printing machine, means for sensing a card in motion, a type bar, a plurality of printing characters arranged on said bar, means adapted to interrupt the movement 100 of said bar to position one of said characters for printing and means controlled by a plurality of differently positioned holes in a card for controlling said first named means while the card is in motion. 105

3. In a card controlled printing machine, a plurality of type elements, record controlled electrically actuated selecting means adapted to select several scattered elements of said plurality of type elements and electrically actuated means 110 controlled by a record and by said selecting means for selecting one of said previously selected elements for operation.

4. In a machine of the class described, means adapted to sense cards in motion, means for 115 successively advancing a group of type to and past the printing position during the passage of a single index point position of a card past the sensing means and means for stopping said type.

5. In a card controlled printing machine, a plurality of groups of type, electrically actuated means controlled by a perforation in a card for selecting a character in each group, and further means controlled by said perforation in the card 125 for selecting one of said groups to present the selected character therein to printing position.

6. In a card controlled printing machine, means for sensing a card in motion, a plurality of type elements movable in synchronism with the card, means for positioning said elements, electric circuits for controlling said positioning means and means controlled by a single perforation in a card for selecting one of said circuits for operation during the movement of the card. 130

7. In a card controlled printing machine, a plurality of groups of type, a plurality of card perforation sensing stations, a selecting device adapted to be controlled by one of said sensing stations for selecting a type in each of said groups, means for synchronizing the operativeness 140 of one of the sensing stations with the passage of a card for operating said device and means controlled by another sensing means and rendered operative by said device for bringing one of said selected type into operation. 145

8. In a card controlled printing machine, a plurality of type, a plurality of sensing stations, means for feeding cards through said stations, one of said stations being responsive to a perforation in separate predetermined positions on a 150

- card, selecting circuits controlled thereby, and type positioning means controlled through said selecting circuits and another of said stations.
9. In a card controlled printing machine, a plurality of type, a plurality of sensing stations, means for feeding cards through said stations, one of said stations being responsive to a perforation in a separate predetermined position on a card, selecting circuits controlled thereby and type positioning means controlled through said selecting circuits, said perforation and another of said stations.
10. In a record controlled machine for operating upon combinational index point records and translating the readings thereon into single timed current impulses comprising a pair of record analyzing means, selecting mechanism settable under control of one of the said analyzing means in accordance with certain predetermined index positions, said selecting mechanism being adapted to cooperate with the other of said analyzing means during the analysis of the other index point positions to convert the readings into single timed current impulses.
11. In a record controlled machine, a type carrier, a pair of card sensing means adapted to sense a perforation in a record card having index points, a magnet controlled by one of said sensing means, contact devices positionable under control of said magnet and means operative under control of the other of said sensing means and said contacts for positioning said type carrier.
12. In a record controlled machine, means for feeding record cards having index points, sensing means cooperating with certain predetermined index points of a card in motion, a plurality of contacts selectively operated under control of said sensing means to close one of said contacts, circuits adapted to be selected by said contacts and a commutator for controlling the time of operation of said selected circuit.
13. In a record controlled printing machine card feeding mechanism adapted to feed perforated cards, a sensing brush for analyzing an index point position while the card is in motion, a plurality of type, means for moving said type to printing position, and circuits controlled by said brush through a perforation in said index point position for selecting any one of said type for printing, said brush being adapted to make continuous contact through the perforation while said type are moving to printing position.
14. In a record controlled printing machine, having upper and lower analyzing brushes for analyzing a card in motion, a selector device controlled by said upper brush, comprising a magnet, a slider differentially positionable thereby and a plurality of contacts, means controlled by said slider for selecting one of said contacts for operation, and means cooperating with said lower brush for completing a circuit through said selected contact.
15. A record controlled printing machine for operating upon combinational index point records, a first set of brushes adapted to sense predetermined index point positions, a second set of brushes, a slider, means for moving said slider synchronously with the movement of a card past the first set of brushes, a magnet controlled by said first set of brushes for positioning said slider, a series of contacts corresponding in number to the positions of said slider, means controlled by said slider for selecting one of said contacts, a plurality of type, means for moving said type to printing position, and distributing means cooperating with said second set of brushes and said selected contact for selecting one of said type for operation.
16. A record controlled printing machine, adapted to be controlled by combinational index point records, a set of brushes adapted to sense predetermined index point positions, a slider, a magnet controlled by said set of brushes for controlling the differential positioning of said slider, a series of contacts corresponding in number to the positions of said slider, means controlled by said slider for selecting one of said contacts, a plurality of type and means controlled by the selected contact for selecting one of said type for operation.
17. In a record controlled cyclically operated printing machine adapted to be controlled by combinational index point records, a set of brushes, one for each column of a record card adapted to sense predetermined index point positions, a pair of sliders for each column, means for operating one of each pair of sliders in alternate cycles, a series of contacts for each pair of sliders and means controlled by a brush for causing said sliders to select one of said contacts for operation.
18. In a record controlled printing machine of the class described, a sensing brush adapted to sense predetermined index point positions, a series of contacts, contact selecting mechanism, means controlled by said brush adapted to position said selecting mechanism and means controlled by said selecting mechanism for selecting one of said contacts for operation.
19. In a record controlled machine, means for sensing cards in motion, a reciprocating type bar having a plurality of type thereon, means for advancing said type to and past a printing position during the passage of a single index point position of a card past the sensing means, and a cyclically operable timing device cooperating with said sensing means for controlling the selection of one of said type.
20. In a card controlled printing machine, a reciprocating type bar having a plurality of groups of type thereon, a plurality of card reading stations adapted to sense perforated cards having index point positions each of said groups of type corresponding to one of said index point positions, the several stations being adapted to control the operation of one of the type in a selected group.
21. In a record controlled printing machine, means for continuously feeding record cards having index points through the machine with an uninterrupted motion, a type bar moving in synchronism with the cards, a plurality of sensing stations, a plurality of numerical and alphabetical characters arranged on said type bar, means cooperating with one of said stations whereby numerical characters are selected by single index points, and means cooperating with more than one station whereby alphabetical characters are selected by combinational index points.
22. In a record controlled machine, the combination with a reciprocating type bar having a plurality of numerical and alphabetical type, an analyzing means comprising two sensing devices one of said sensing devices responsive to a single index point of a record card for selecting the numerical type and both sets conjointly responsive to combinational index points for selecting the alphabetical type.

JOHN ROYDEN PEIRCE. 150
